UNITED STATES PATENT OFFICE.

LEON H. FISH, OF ALBANY, OREGON.

STATIONARY CUSPIDOR.

Application filed December 31, 1921. Serial No. 526,185.

To all whom it may concern:

Be it known that I, LEON H. FISH, a citizen of the United States, residing at Albany, in the county of Linn and State of Oregon, have invented certain new and useful Improvements in Stationary Cuspidors, of which the following is a specification, reference being had to the accompanying drawings.

10 This invention relates to sanitary cuspidors, and more particularly to a stationary cuspidor.

An object of the invention is to provide a cuspidor of this character which is self-draining and is adapted to be substantially embedded in the floor of a vehicle or building, the structure being capable of supporting the weight of a person stepping on the same.

20 It is another object of the invention to provide a cuspidor of this character which can be inserted in the floor of a vehicle and provided with a cover to cover the bowl of the cuspidor, said cover substantially forming a part of the floor of the vehicle.

It is a further object of the invention to provide a cuspidor of this character wherein the cover is hinged to the bowl of the cuspidor and normally urged to its open position through the medium of springs, means being provided for fastening the cover in its closed position.

30 It is still a further object of the invention to provide a cuspidor of this character adapted to extend through an opening provided in the floor of a vehicle or building, the edges of the cuspidor being formed for engagement with means carried by the cover to not only support the cover when the same is under strain in its closed position, but to also prevent the admission of air into the vehicle or building from the cuspidor to a large extent.

With these and other objects in view, the invention consists in the improved construction and arrangement of parts to be hereinafter more particularly described, fully claimed and illustrated in the accompanying drawings, in which:

40 Figure 1 is a sectional view of a stationary sanitary cuspidor constructed in accordance with an embodiment of the invention.

Figure 2 is a top plan view with the cover in its open position:

50 Figure 3 is a top plan view with the cover partially closed;

Figure 4 is a sectional view taken on the line 4—4 of Figure 2; and

Figure 5 is a fragmentary and sectional view of the cuspidor and floor, showing the construction of the bumper.

Referring to the drawings, 4 designates a floor which may be either the floor in the room of a building or the floor of a vehicle, such as an automobile, railway or aero car, an opening 5 being provided in the floor, said opening being substantially U-shaped. A plate 6 is provided, said plate being formed to provide a bowl 7, the intermediate portion of the bottom of the bowl having an annular flange adapted to provide an outlet 8 for the bowl 7, the sides of the bowl being substantially curved to direct the contents of the cuspidor toward the outlet 8. The exterior face of the outlet 8 is threaded. The edge of the plate is extended outwardly substantially in angular relation to the bowl 7 to provide a supporting flange 9, said flange being substantially U-shaped. The end portions 9 of the flange are enlarged so as to extend from the outer edge of the flange to the edge of the bowl and at the same time cover the portion of the opening in the floor disposed between the edge of the bowl and the flange. A bead or roll 10 is formed at the junction of the flange 9 with the bowl, said bead or roll being disposed at the edge of the opening 6 so that the same projects above the upper face of the flange 9, the bead terminating at the edge 11 of the plate. The bead is suitable for a number of purposes, for instance, when the cuspidor is open or in use, should an article be dropped upon the floor and roll toward the cuspidor, the bead or roll 10 will prevent the same from rolling into the bowl of the cuspidor. It is the main purpose, however, of the bead to provide a substantial support of the cover to be hereinafter described.

100 The edge 11 of the plate from which the bowl and flange are formed is provided with a plurality of hinged knuckles 12, the end knuckles of said edge being slotted for the reception of the end of a spring 13, the spring being disposed within the end knuckle, one end of the spring extended through a slot 13^a in the knuckle to prevent turning of the the spring. Projecting from the forward edge of the plate 6 is an extension 14 having a slot 15 below which a casing 16 is disposed. Slidably within

the casing 16 is a bolt 17, a spring 18 being disposed between the end of the bolt and the forward end of the casing 16. A finger piece 19 is connected to the bolt, extends 5 through the slot 15 and above the extension. A protector or dome 20 is secured to the extension, said dome having its upper portion cut away as at 21 to permit the insertion of the finger of the user, the finger piece 19 being normally disposed beneath the dome to prevent the finger piece from being damaged.

A cover 22 is provided, said cover consisting of a plate having its edge 23 rolled or 15 beaded, while the plate inwardly of said edge is substantially dished to provide a relatively shallow dome, the bead 23 extending above the upper surface of the dome. By the formation of the bead, a channel is 20 provided for the reception of the bead or roll 10 of the bowl. The beaded portions of the cover and bowl cooperate to substantially provide hangers for the cover so that in the event a person steps upon the cover 25 there is no danger of the same being forced inwardly of the bowl. At the same time, this cooperation to a large extent, prevents the admission of air from the bowl into the vehicle or room. The cover, similar to the 30 bowl, is made from a plate, the edges 24 of the plate or cover being provided with a plurality of knuckles 25 adapted to extend between and register with the knuckles 12 of the bowl. A bolt 26 is passed through said 35 registering knuckles for connecting the cover to the plate, the inner ends of the springs 12 being disposed within the rolled or beaded portion of the cover so as to normally urge the cover to its open position. 40 The end portions of the bead 10 of the bowl are provided with recesses 27 adapted to receive said ends of the springs so as to prevent interference with the closing of the cover. The edge of the cover remote from 45 the hinged connection thereof, is provided with an extension 28 having an opening 29 for the reception of the bolt 17. The extension thereby provides a keeper adapted to extend through a slot 28^a provided in the 50 plate 6 adjacent the extension 13 so that the keeper may extend into the casing 16 for engagement with the bolt to prevent movement of the cover by the springs of the hinge. 55 In view of the tension of the springs and the rapidity with which the cover is opened, a bumper is provided to prevent contact of the cover with the floor when the same is swung to its open position. This bumper 60 consists of a container 30 having ears 31 projecting from one end thereof, said ears being adapted to extend between the knuckles 24 and 12 of the hinged connection, the ears being provided with openings for the 65 reception of a portion of the bolt 26. The upper portion of the container is tapered

longitudinally and is adapted to receive a block of rubber 32, the rubber being adapted to cushion the cover when the same comes in contact therewith.

When the cover is swung to its closed position, the keeper 28 engages the beveled face of the bolt 17 and locks the cover substantially flush with the surface of the floor, the only projecting portions above the opening in the floor being the beaded or rolled portions of the plate 6 and the cover. When it is desired to use the cuspidor the user operates the bolt 19 through the medium of the finger piece so as to release the keeper and permit the cover to swing to its open position. In connection with the cuspidor, an extension or draining pipe 33 is provided, said pipe being connected to the outlet 8 of the bowl through the medium of a coupling 34 so that the conduit may be swung to any 85 position to permit drainage of the cuspidor. This connection of the drain pipe permits the same to be turned away from the direction of draft under a car caused by the forward movement of the car so that a draft of 90 air passing beneath the car will cause a suction in the pipe 33, thereby producing a self-drainage or cleaning action for the cuspidor when the vehicle is in motion.

From the foregoing it will be readily seen 95 that this invention provides a novel form of stationary sanitary cuspidor having a lid which is capable of being automatically swung to its open position upon release of the latch and wherein the bowl of the cuspidor, in view of its simple arrangement, may be easily cleaned or flushed and all these features are possessed by a device that may be constructed from a small amount of material.

What is claimed is:—

1. A cuspidor comprising a bowl-shaped member having its bottom provided with an outlet and having its upper edge merging into an attaching plate formed with an upstanding ridge, one end of the attaching plate being semi-circular and the other end being straight across, the ridge being spaced from and parallel with the edge of the attaching plate and having its ends terminating at the straight edge of the attaching plate, and a cover of concavo-convex shape in cross section and having a general shape corresponding to that of said attaching plate, the cover being hinged at the straight edge of the attaching plate and being formed with a pressed peripheral groove matingly engaging upon the ridge of the attaching plate.

2. In a cuspidor including a bowl portion 125 and an attaching plate portion at the upper edge thereof, a cover hinged upon one edge of the attaching plate portion and provided with a depending slotted lug constituting a keeper, a guard housing on the attaching 130

plate substantially U-shaped in plan and having its top portion partially cut away, a guide housing mounted beneath said attaching plate at a point opposite said first named housing and recessed into the surface upon which the cuspidor is secured, a spring pressed bolt slidable within said guide housing and adapted to engage within the slotted lug of the cover, said attaching plate portion being formed with a slot communicating with both housings, and an upstanding

finger piece carried by the bolt, extending through said last named slot and projecting into the first named housing and engageable whereby to retract the bolt to permit opening of the cover, the cut away top of the first named housing permitting ready access to said finger piece. 15

In testimony whereof I hereunto affix my signature.

LEON H. FISH.
